MARTIN L. HUNKER, OF WHEELING, WEST VIRGINIA, ASSIGNOR TO WHEELING CORRUGATING COMPANY, OF WHEELING, WEST VIRGINIA, A CORPORATION OF WEST VIRGINIA.

APPARATUS FOR FORMING CORRUGATED ELBOWS.

1,203,346.

Specification of Letters Patent. Patented Oct. 31, 1916.

Application filed April 17, 1916. Serial No. 91,574.

To all whom it may concern:

Be it known that I, MARTIN L. HUNKER, a citizen of the United States of America, and resident of Wheeling, county of Ohio, and State of West Virginia, have invented 5 certain new and useful Improvements in Apparatus for Forming Corrugated Elbows, of which the following is a specification.

10 This invention relates to apparatus for forming corrugated sheet-metal elbows, and it has for its primary object to provide a simple mechanism whereby a plurality of plait are formed in a sheet-metal tube 15 blank for producing an elbow and also whereby said blank is acted upon in such manner that the completed elbow has a corrugated form.

In describing the invention in detail, reference is herein had to the accompanying drawings, forming a part of this specification, in which—

Figure 1 is a partial longitudinal section of the mandrel and certain associated parts, 25 the same being shown occupying the positions assumed at the conclusion of the crimp-forming operation and just prior to the shifting operation in which the crimp is turned back to form a plait; Fig. 2 is a section on line 2—2, Fig. 1, showing a face view of the crimping disk; Fig. 3 is a section on line 3—3, Fig. 1; Fig. 4 is a front elevation of the rearmost tube-embracing jaws, showing parts of the jaw-operating 35 means; Fig. 5 is a section on the line 5—5, Fig. 4; Fig. 6 is a detail view in front elevation of the segmental plait-flattening jaws; and Fig. 7 is a side elevation of an elbow formed by means of the invention.

40 The mechanism by means of which the parts composing the present invention are actuated is substantially identical throughout with that disclosed in my pending application for patent for elbow forming machine, filed March 4, 1916, Serial No. 82,040, wherein the manufacturer of plain, or uncorrugated, elbows is provided for. Therefore, the description herein given will be limited to the specific parts involved in the 45 present invention, reference being had to said prior application for a complete understanding of the details of construction of the mechanism whereby said parts are actuated.

50 Referring to the drawings, 1 indicates a

stationary horizontal hollow mandrel which has an eccentrically disposed longitudinal bore within which is mounted a rotatable sleeve 2. Said sleeve is also provided with an eccentrically disposed longitudinal bore in which is rotatably mounted a shaft 3. The front ends of said sleeve and shaft are flush with the corresponding end of the mandrel, and extending forward from the front end of said shaft is an integral wrist 65 4 having an eccentric disposition with respect to the axis of said shaft. The location of said wrist is such that, while it is eccentric with respect to said shaft, it is concentric with respect to the axis of the mandrel 70 when the said parts occupy their normal positions. Loosely mounted, or having free rotary movement on said wrist, and located close against the flush ends of the mandrel, sleeve and shaft, is a crimping disk 5 having 75 a less diameter than said mandrel and the periphery of which is of regular scalloped outline, the number of scallops corresponding with the number of corrugations in the tube. Said disk has its peripheral edge 80 beveled and is designed to swing throughout an eccentric path with the travel of the wrist for forming in the tube or tube blank 6 outwardly pressed crimps 7 which shall subsequently be thrown back upon the body 85 of the blank in the form of plait, as shown at 8 in Fig. 7.

Keyed upon the wrist 4 close in front of the disk 5 and disposed in an eccentric position with respect to the latter is a relatively smaller circular wheel or disk 9, and freely rotatable upon said disk 9 is a ring 10 which is disposed eccentrically with respect to said disk 9 and concentrically with respect to the disk 5. Said disk 9 follows the eccentric movements of the disk 5 as the latter is thrust outward for forming the crimps in the tube blank 6 and is designed to engage the inner surface of said blank adjacent to the portion of the latter which is being acted upon by said disk 5, and thus to coöperate with the outer blank-embracing jaws for preventing distortion or buckling of the blank at points directly in front of the disk 5 during the crimp-forming operation. Since the ring 10 is freely rotatable, it at all times occupies a position wherein its heavier side is lowermost, as shown in Fig. 1.

The outer surface of the mandrel 1 is 110

corrugated longitudinally to correspond with the corrugations desired for the elbow, and the tube-blank 6 is in like manner corrugated prior to its mounting upon the 5 mandrel, as shown in Fig. 3.

Normally disposed in embracing relation to the blank adjacent to the front end of the mandrel are two pairs of complementary jaw sections 11 and 12, the former being located 10 forward of and the latter rearward of the position in which the crimp 7 is formed in the blank by the action of the crimping disk 5, said jaw sections corresponding to those described in my said pending application, except that the inner faces thereof are shaped to correspond with the corrugated surface to be embraced thereby.

The segmental crimp-flattening jaws 14 correspond with those disclosed in my said 20 pending application, except that the tube-embracing surfaces of said jaws are shaped to correspond with the corrugated form of the blank, as shown in Fig. 6.

As hereinbefore indicated, the operations 25 of the various parts are identical with those of the corresponding parts in my pending application, to which reference is made for a full description of said operations.

As will be readily understood, the disk 5 30 is caused by rotation of the sleeve 2 and shaft 3 to traverse an eccentric path relative to the mandrel 1, wherein its beveled peripheral edge is projected outward beyond the periphery of the mandrel, producing the 35 outwardly pressed V-shaped crimp 7 shown in Fig. 1, said crimp having its greatest dimension at the uppermost part of the blank and gradually diminishing to the lowermost part. In traveling throughout its said 40 eccentric path, said disk 5 does not itself rotate except to the relatively slight extent which is permitted by the scallops thereof interengaging with the corrugations of the blank.

45 What is claimed is:—

1. In a machine for forming corrugated sheet-metal elbows, a mandrel having a longitudinally corrugated exterior and having an eccentrically disposed longitudinal bore, 50 a sleeve rotatably mounted within said bore, said sleeve having an eccentrically disposed

bore, a shaft rotatably mounted in the last-mentioned bore, said sleeve and shaft having their front ends flush with the end of said mandrel, an eccentrically disposed wrist 55 carried by said shaft, a crimping disk loosely mounted on said wrist, said disk having a scalloped periphery, a pair of pivoted jaws embracing the front end of said mandrel, and a second pair of pivoted jaws disposed 60 in front of the position of said disk and adapted to assume embracing relation to a tube blank carried by said mandrel, said jaws having their inner faces shaped to conform to the surface of said blank, the 65 foremost of said pairs of jaws being adapted for rearward swinging movement for inclining rearwardly crimps formed in said blank.

2. In a machine for forming corrugated 70 sheet-metal elbows, a mandrel having a longitudinally corrugated exterior and having an eccentrically disposed longitudinal bore, a sleeve rotatably mounted within said bore, said sleeve having an eccentrically disposed 75 bore, a shaft rotatably mounted in the last-mentioned bore, said sleeve and shaft having their front ends flush with the end of said mandrel, an eccentrically disposed wrist carried by said shaft, a crimping disk loosely 80 mounted on said wrist, said disk having a scalloped periphery, a pair of pivoted jaws embracing the front end of said mandrel, and a second pair of pivoted jaws disposed in front of the position of said disk and 85 adapted to assume embracing relation to a tube blank carried by said mandrel, said jaws having their inner faces shaped to conform to the surface of said blank, the foremost of said pairs of jaws being adapted 90 for rearward swinging movement for closing crimps formed in the blank and for inclining said crimps rearward, and radially movable jaws for flattening the inclined crimps to form seams. 95

In testimony whereof I affix my signature in presence of two subscribing witnesses.

MARTIN L. HUNKER.
